UNITED STATES PATENT OFFICE.

HARRISON D. McFADDIN, OF EAST ORANGE, NEW JERSEY.

LAMP-FIXTURE.

1,195,144.

Specification of Letters Patent. Patented Aug. 15, 1916.

Application filed October 27, 1914. Serial No. 868,827.

To all whom it may concern:

Be it known that I, HARRISON D. McFADDIN, a citizen of the United States, residing in East Orange, county of Essex, and State of New Jersey, have invented a certain new and useful Lamp-Fixture, of which the following is a specification.

This invention is a lamp fixture, and the object of the invention is to support a lamp and shade in a particularly simple, attractive and effective manner.

The invention will be described particularly in connection with its application as an electric light fixture, although it will be apparent that certain advantages may be availed of in lamps of other types.

In lamp shades or reflectors for electric lights, as heretofore constructed, it has been customary to form an imperforate reflector or shade and to subsequently drill holes or cut openings therein, usually in opposing relation, to permit of its being rotatably mounted on the trunnions forming a part of the lamp fixture. The operation of drilling the holes is not only expensive, but results in a considerable loss from breakage and, further, weakens the resulting structure.

The present invention, in contradistinction to those prior art devices wherein the shade is supported on trunnions passing through apertures in the shade, is supported preferably from its lower edge and in such manner that a pivotal support is secured without necessitating the employment of trunnions.

The present invention, moreover, permits of the shade's being detached and a new one replaced without necessitating the removal of the lamp socket or interfering with the wiring, said wiring being preferably invisibly incased within the shade-supporting bracket.

A further feature of the invention resides in the fact that the clamps by which the reflector is secured to the bracket are positioned interiorly of the reflector, whereby, when the reflector becomes heated, the expansion thereof is in a direction away from the clamps, thereby reducing the pressure on the clamps with consequent less danger of breakage of the glass from which said reflectors are usually made.

The absence of trunnions in the lamp fixture of the present invention, as well as the fact that the clamping devices are relatively

small and positioned near the lower edge of the reflector, result in comparative freedom from shadows, in that the reflecting surface is comparatively little obscured.

In the preferred practical embodiment of the invention, the supporting bracket consists of a channeled member, shaped to correspond to the contour of the reflector which it is desired to support, which channel is adapted to receive the lower edge, or a portion thereof, of said reflector. The lower edge of the reflector is preferably formed with an offset, with which clamping members on the bracket coöperate to fixedly secure the reflector in position.

Features of the invention, other than those specified, will be apparent from the hereinafter detailed description taken in conjunction with the accompanying drawings.

In the accompanying drawings, I have illustrated one practical embodiment of the invention, but the construction shown therein is to be understood as illustrative, only, and not as defining the limits of the invention.

Figure 1 is a side elevation of a lamp bracket embodying the present invention. Fig. 2 is an underneath plan view of the same. Fig. 3 is a top plan view of the fixture with the shade or reflector detached. Fig. 4 is a front elevation of Fig. 3. Fig. 5 is a section taken on line 5—5 of Fig. 4, showing the manner in which the reflector or shade is retained within the fixture. Fig. 6 is a perspective detail of one of a plurality of clamping means which I employ, and Fig. 7 is a transverse section of the preferred form of reflector.

Referring to the drawings, the shade or reflector supporting member is denoted by the reference numeral A. This supporting member is mounted by means of any suitable pivotal connection B on a wall bracket, portable standard, or the like. Supporting member A is channeled in cross-section throughout its entire extent, so as to be adapted to receive the lower edge of a shade. It is, therefore, in shape substantially that of the contour of the shade, or that portion thereof with which it is adapted to coöperate. As shown in Figs. 1 and 2, I preferably proportion supporting member A so as to embrace substantially one-half of the lower edge of the shade. Thus, when

a shade C is placed on the fixture with a portion of its lower edge positioned within the channel of supporting member A, the weight of said shade will be distributed throughout the entire extent of the supporting member, and the strain on said supporting member will be minimized.

In order that convenient means may be provided for maintaining the shade against inadvertent displacement from its supporting member and to properly support the weight of the shade on said member, said shade is preferably provided with a hooded lateral extension c, which, when the shade is in place, is housed within the channel of member A. Member A, to increase its esthetic appearance and strength, is preferably tapered in depth from the plug a, which forms its support, to the free ends thereof, and the channel interiorly of said member is, therefore, likewise tapered in depth. The offsetting of shade C, as at c, provides on the exterior of the shade a shoulder c', adapted to rest upon the upper edge of supporting member A, at the outer side of the channel thereof, and form a seat for the shade upon said supporting member. Moreover, the offsetting of portion c of the shade forms a shoulder c² interiorly thereof, which I utilize in locking the shade against inadvertent displacement from the channel of supporting member A.

Positioned within the channel of supporting member A, in recesses d, is a plurality of clamping members D, one of which is shown in perspective in Fig. 6. These clamping members are pivoted, at d', to the interior wall of the supporting member, and, at the opposite ends of the clamping members from their points of pivoting, are laterally extending flanges d², adapted, when the clamping members are folded down into the recesses d, to engage with shoulder c² of shade C. Each clamping member D is provided with a lug e, projecting laterally in an opposite direction from flange d², which lug is adapted to overlie the interior edge of supporting member A. Each lug e is provided with a threaded tap e', into which is adapted to be screwed a bolt e² mounted on a bracket e³ on the interior of supporting member A. A collar e⁴ is fixed on each of said bolts to preclude their longitudinal movement.

It will be manifest, from the foregoing description of the clamping means, that each clamping member is pivotal about its point of attachment d', and may be either folded into the recesses d of supporting member A into its closed position, or swung upwardly into the vertical, open position illustrated by clamping member D' in Fig. 4. When it is desired to position a shade upon supporting member A, all of the clamping members D are swung to their open position

and thereby allow of the positioning of the offset portion of the lower edge of the shade in the channel of supporting member A. When this has been accomplished, clamping members D are swung to their closed position, whereupon flanges d² of said clamping members will engage with shoulder c² of the shade. If the bolts e² are now operated so as to engage with the threaded aperture e' of lug e, of each clamping member D, said bolts will operate to pull down the clamping members tightly into engagement with shoulder c² of the lamp shade, and lock the same in the channel against inadvertent displacement.

The lamp socket F, which is adapted to receive the threaded plug of an electric lamp or bulb F', is preferably supported upon the fixture by virtue of the gripping action of a split ring f, which is fixed to the interior of supporting member A and may be regulated by screw f' to grip or release socket F. In initially assembling the bracket, split ring f is formed integral with, or is fixedly attached to, supporting member A, the base of socket F inserted thereinto, and screw f' tightened to cause ring f to tightly grip said socket. It will be noted, in Fig. 3, that the socket and clamping means are positioned interiorly of the channel whereby a shade may be removed from the fixture and another replaced, without necessitating the removal, or any manipulation whatever, of the lamp socket or lamp F', supported therein. The current for operating the lamp is fed through wires g g', which are led through the pivotal connection B and threaded plug a into the channel of the supporting member, thence through said channel, below the edge of the lamp shade supported therein, to lamp socket F, as clearly shown in Figs. 1, 2 and 3. It will be noted, from Fig. 5, that the supporting of lamp shade C upon shoulder c' precludes said lamp shade from projecting to the bottom of the channel and thereby leaves a space along the bottom thereof, which forms a conduit for the wires g g', and said wires are, therefore, entirely obscured from view.

It will be manifest, from the foregoing description, that the positioning of the shade clamping devices interiorly of the supporting member, as well as the passing of the wires through a closed conduit, renders the fixture entirely free from all unsightly projections, and materially increases its esthetic appearance. Moreover, the fixture conforms to the contour, and, in every way, follows the general lines, of the shade, whereby said fixture harmonizes with said shade, with the result that a very pleasing appearance is secured. Furthermore, the fixture is compact in every detail. There are no projecting arms, thumb-nuts, and the like, which are common in devices now in

use, and the inherent objection of shadows in these devices is obviated. It will further appear that, since the clamping members are positioned interiorly of the shade, the 5 expansion of said shade, when heated, will cause the portions of said shade held by said clamps to recede, rather than to bind, at the clamping points. This obviates all tendency to breakage under expansion, an objection 10 inherent in practically all of the lamps now on the market. The positioning of the lamp socket interiorly of the shade and the supporting thereof entirely within the inner contour of said shade, and the leading of 15 the current-supplying wires through the channel of the supporting member beneath the edge of said shade, obviate the necessity, inherent in prior devices, of removing or dismantling a portion of the lighting sys- 20 tem or wiring, when removing or replacing a lamp shade on the bracket. A further feature of advantage resides in the improved manner of fixedly mounting the lamp bracket on the fixture, by means of the split 25 ring shown. By this method, the base of the lamp socket is practically in contact with the interior of the shade or, in other words, is positioned closer to the end of the shade than has heretofore been possible. 30 This allows of the positioning of the lamp more centrally within the reflector and insures a more perfect dissemination of the light.

In the foregoing specification and in the 35 accompanying drawings, I have illustrated the preferred practical embodiment of my invention. It will be understood that I do not restrict myself to the specific details of construction therein described and illus- 40 trated—*e. g.*, there are many clamping means which may be utilized in securing the shade in position within the channel of the supporting member and I do, therefore, wish it understood that I consider my in- 45 vention as broadly novel as commensurate with the appended claims.

Having thus fully described the invention, what I claim as new, and desire to secure by Letters Patent, is:—

50 1. In a lamp bracket, a channeled supporting member adapted to conform to, and house, the lower edge of a reflector, the chan- 55 nel of the supporting member being of such depth as to leave a conduit intermediate the edge of the reflector and the base of the channel, a lamp socket mounted on the sup- 60 porting member, and electric wires passing through the conduit intermediate the bottom of the channel and the edge of the reflector, and in communication with the lamp socket, whereby said wires are concealed from view.

2. In a lamp bracket, a channeled sup- 65 porting member adapted to support a re- 70 flector, a lamp socket mounted on said sup- 75 porting member, and electric wires housed

within the channel of the supporting mem- 70 ber and having connection with the lamp 75 socket.

3. In a lamp bracket, a channeled sup- 70 porting member adapted to support a reflec- 75 tor, the lower edge of which reflector is adapted to enter the channel in the support- 80 ing member, and electric wires also posi- 85 tioned in the channel of the supporting member and concealed from view when the reflector is in place.

4. In a lamp bracket, a channeled sup- 80 porting member shaped to conform to, and house, the edge of a reflector, the support- 85 ing member being so constructed that the edge of said reflector extends into the chan- 90 nel thereof, the reflector being supported on the upper edge of the channeled member whereby a conduit is left intermediate the edge of the reflector and the base of the channel, a lamp socket, and electric wires ex- 95 tends through said conduit and communi- 100 cating with the lamp socket.

5. In a lamp bracket, a channeled sup- 90 porting member shaped to conform to, and house, the edge of a reflector, the channel of 95 the supporting member being of such depth as to leave a conduit intermediate the edge of said reflector and the base of the channel when the reflector is properly seated therein, a lamp socket mounted on the supporting member, and electric wires passing through 100 the conduit intermediate the bottom of the channel and the edge of the reflector and se- 105 cured to the lamp socket whereby said wires are maintained in concealed position and the reflector may be removed without interfer- 110 ing with said wires.

6. In a lamp bracket, a channeled sup- 105 porting member shaped to conform to, and house, the edge of a reflector, the channel of 110 the supporting member being of such size as to leave a conduit therein when the edge of the reflector is normally seated in said channel, and a lamp socket mounted on the sup- 115 porting member, whereby the electric wiring of the lamp may be led through the said conduit in the channel and thence to the lamp socket for the purpose of incasing said wiring and yet permit of the removal of 120 the reflector without interfering with the wiring.

7. In a lamp bracket, a supporting mem- 120 ber shaped to conform to, and adapted to in- 125 close, a portion of the edge of a reflector, said reflector having a main portion and a hooded lateral extension, which hooded lat- 130 eral extension is housed by the supporting bracket, the remainder of the contour of the reflector being left free and unobstructed, and means for locking the reflector in place upon the supporting bracket.

8. In a lamp bracket, a channeled sup- 130 porting member shaped to conform to a portion of the edge of a reflector, which por-

tion of the reflector is formed with a hooded, lateral extension housed within the supporting member, the remainder of the contour of the reflector being left free and unobstructed.

9. In a lamp bracket, the combination of a reflector embodying a main portion and a hooded lateral projection extending around a portion of the edge of the reflector, and a 10 channelled supporting member coöoperating with the hooded portion of the reflector, said portion being adapted to enter the channel in the supporting member, leaving the remainder of the contour of the reflector free 15 and unobstructed.

10. In a lamp bracket, the combination of a reflector, a reflector supporting member shaped to conform to, and extend around, a portion of the edge of the reflector and leave 20 the remainder of the edge free and unobstructed, and means for locking the reflector to the supporting member.

11. A lamp fixture embodying, in combination, a reflector, the edge of which is off-

set interiorly of the reflector for a portion of 25 its extent, a channelled supporting member shaped to conform to the contour of the reflector, the channel of which supporting member is adapted to receive the offset portion of said reflector while the shoulder on 30 the exterior of the reflector, adjacent the offset portion thereof, is seated upon the edge of the channelled member, whereby the free edge of the offset portion of the reflector is maintained in spaced relation to, and out 35 of engagement with, the base of the channel of the supporting member, and a clamping member adapted to engage with the shoulder on the interior of the reflector for locking said reflector to its supporting member. 40

In testimony whereof I have signed my name to this specification in the presence of two subscribing witnesses.

HARRISON D. McFADDIN.
